UNITED STATES PATENT OFFICE.

ANDREW PAUL AND JOHN A. SMITH, OF PHILADELPHIA, PENNSYLVANIA

FOLDABLE STAND.

1,206,364.

Specification of Letters Patent.

Patented Nov. 28, 1916.

Application filed April 17, 1915. Serial No. 21,951.

To all whom it may concern:

Be it known that we, ANDREW PAUL and JOHN A. SMITH, citizens of the United States, residing in the city and county of Philadelphia and State of Pennsylvania, have invented certain new and useful Improvements in Foldable Stands, of which the following is a specification.

Our invention relates to improvements in foldable stands employing a central post, legs pivoted to the post, a collar slideable on the post, braces connecting the legs and the collar and means to hold the collar in position upon the post when the stand is in use.

The object of our invention is to provide a novel, simple, inexpensive and efficient means to hold the collar in position upon the post when the stand is in use and to permit the stand to be readily folded and unfolded as desired.

With this object in view, our invented stand consists of the elements and combinations of them hereinafter fully described and particularly claimed.

In the accompanying drawings, illustrating our invention, Figure 1 is a front elevation of a foldable stand embodying our invention. Fig. 2 is a vertical section, on line 2—2 of Fig. 1. Fig. 3 is a horizontal section, on line 3—3 of Fig. 2.

Referring to the drawings, 4 designates a central post provided with a bracket 5 which is secured on the lower end thereof. The bracket 5 is provided with outwardly-extending lugs to which are pivoted the upper ends of downwardly and outwardly diverging legs 6. Slidable vertically upon the post 4, above the bracket 5, is a collar 7 provided with outwardly-extending lugs which have the upper ends of braces 8 pivoted thereto as shown. The lower ends of the braces 8 are pivoted to the legs 6, and the parts thus far described are related to each other so that by raising the collar 7 from the position shown upon the post 4, the legs 6 and braces 8 will be raised and folded inwardly adjacent to the post 4, and that by then lowering the collar 7 to the position shown, the legs 6 and braces 8 will be unfolded into the condition shown, in the usual manner common to well known music and other stands.

The bracket 5 is provided with a lug or arm 9 which extends upwardly therefrom adjacent to the post 4 and has its upper end bifurcated for the reception of the lower

portion of a latch arm 10 which is pivoted at 11, to the lug 9. The upper portion of the latch arm 10 is forced outwardly by the action of a coiled spring 12 which is housed within an opening or socket formed in an enlarged portion 13 of the arm 10 and bearing against the arm 10 and the post 4, the wall of the socket surrounding the spring 12 and holding it in place. Outward movement of the upper portion of the latch arm 10 is limited by the lower portion 14 thereof engaging the post 4.

When the parts are in the position shown in the drawings, the upper end portion of the latch arm 10 extends through and above an opening 15 which extends longitudinally through the collar 7 outwardly of the post 4; and the arm 10 is provided with a tooth or projection 16 which extends outwardly above the collar 7 and is adapted to engage the top thereof and prevent upward movement of the collar upon the post 4. Downward movement of the collar 7 is prevented by the enlarged portion 13 of the arm 10, the portion 13 extending outwardly and forming a stop spaced from the tooth or projection 16 a distance equal or substantially equal to the length of the collar 7, so that when the parts are in the position shown, the collar 7 will be held by and between the parts 16 and 13 against either up or down vertical displacement upon the post 4.

When it is desired to raise the collar 7 upon the post 4 to raise the legs 6 and braces 8 and fold them inwardly, the upper end of the latch arm 10 is pressed by hand toward the post 4 until the bottom of the projection 16 is disengaged from the top of the collar 7, thus releasing the collar and permitting it to slide upwardly upon the post for the folding operation. After the collar 7 has been raised above the latch arm 10, the latch arm is moved back to the position shown by the spring 12 and the upper beveled end 17 of the latch arm 10 is directly beneath the outer wall 18 of the longitudinal opening 15 in the collar 7, so that when the collar 7 is again moved downwardly upon the post 4, the wall 18 will engage the beveled end 17 of the arm 10 and force it inwardly and cause it to enter the opening 15, and, after the collar 7 is moved down against the stop 13, the spring 12 will force the upper end of the latch arm 10 outwardly, moving the tooth or projection 16

over the upper end of the collar 7 and locking the stand in the unfolded condition shown in the drawings.

While our invention may be used in connection with foldable stands of any character, we have illustrated it in the drawings as applied to a music stand whereof the post 4 forms the lower section of a telescopic standard 19 which supports a foldable music rack 20 at its upper end.

We claim:

1. In a foldable stand, the combination of a central post, legs pivoted to parts fixed to the lower end of said post, a collar 15 slideable on said post and having a longitudinal opening extending therethrough outwardly of said post, braces connecting said legs and said collar and pivoted thereto, and a latch arm connected to a part fixed on 20 said post between the lower end thereof and said collar and having a free end extending upwardly and adapted to pass through said opening in said collar, the upper end of said latch arm having an outwardly extending 25 projection adapted to engage over the top of said collar and prevent its upward movement upon said post.

2. In a foldable stand, the combination of a central post, legs pivoted to parts fixed 30 to the lower end of said post, a collar slideable on said post and having a longitudinal opening extending therethrough outwardly of said post, braces connecting said legs and said collar and pivoted thereto, a latch arm pivoted to a part fixed on 35 said post between the lower end thereof and

said collar and having a free end extending upwardly and adapted to pass through said opening in said collar when said collar is moved longitudinally, and a spring tending 40 to force the upper end of said arm outwardly from said post, the lower end of said arm being adapted to engage said post and limit the outward movement of the upper end thereof and prevent it from being moved out of alinement with the opening in 45 said collar, the upper end of said latch arm having an outwardly extending projection adapted to engage over the top of said collar and prevent its upward movement upon 50 said post.

3. In a foldable stand, the combination of a central post, legs pivoted to parts fixed to the lower end of said post, a collar slideable on said post, braces connecting said 55 legs and said collar and pivoted thereto, a latch arm pivoted to a part fixed on said post and provided with an outwardly extending hollow stop projection adapted to engage said collar and limit the movement 60 thereof, and a spring housed within said projection and interposed between said latch arm and said post and tending to force said latch arm outwardly, the upper end of said latch arm having an outwardly extending 65 projection adapted to engage said collar and prevent its upward movement upon said post.

In testimony whereof we affix our signatures hereto.

ANDREW PAUL.
JOHN A. SMITH.
